UNITED STATES PATENT OFFICE

172,797

OUTDOOR COOKER

William T. Long, Snyder, Tex.

Application February 26, 1954, Serial No. 29,227

Term of patent 14 years

(Cl. D81—10)

To all whom it may concern:

Be it known that I, William T. Long, a citizen of the United States, residing at Snyder, in the county of Scurry and State of Texas, have invented a new, original, and ornamental Design for an Outdoor Cooker, of which the following is a specification, reference being had to the accompanying drawing, forming part thereof.

Fig. 1 is a perspective view of the front of an outdoor cooker, showing my new design.

Fig. 2 is a front elevation of the same.

Fig. 3 is a perspective view of the rear of the same.

Fig. 4 is a top plan view of the same.

I claim:

The ornamental design for an outdoor cooker, as shown.
